UNITED STATES PATENT OFFICE.

CHARLES F. LEFEVER, OF PLYMOUTH, MICHIGAN, ASSIGNOR TO DAISY MANUFACTURING COMPANY, OF PLYMOUTH, MICHIGAN, A CORPORATION OF MICHIGAN.

AIR GUN.

Application filed April 19, 1926. Serial No. 103,119.

The invention relates to air guns of that type in which the spring for propelling the plunger is compressed by the operation of a lever. One of the objects of the invention 5 is the provision of an improved air gun having a simple construction of parts so arranged that they may be readily and quickly assembled. Another object is to provide an air gun in which the spring is compressed by shifting one of its abutments. Further objects of the invention reside in the novel features of construction and combinations and arrangements of parts as more fully herein- 10 after set forth.

15 In the drawings:

Figure 1 is a side elevation of the gun;

Figures 2 and 3 are vertical longitudinal sections thereof;

Figure 4 is a side elevation of the plunger 20 assembly;

Figure 5 is a plan view thereof;

Figures 6 and 7 are vertical longitudinal sections showing the barrel and stock assemblies prior to final assembly;

25 Figure 8 is a cross section on the line 8—8 of Figure 4;

Figures 9 and 10 are cross sections respectively on the lines 9—9 and 10—10 of Figure 2.

30 A is the false barrel which may be of any suitable construction provided with a forward plunger abutment B to which the true barrel C is attached. The bottom portion of this barrel is provided with a reinforcement strip D which near its rear end has a downwardly extending embossment E wedge shaped in longitudinal section and notched at F. G is the frame which is formed from a single sheet metal blank bent into inverted

35 U-shaped cross section with its lower ends turned inward to form in a portion of its length abutting flanges H and centrally down turned spaced flanges I. The latter form a fulcrum for the lever J and in rear of this 40 fulcrum are the flaring flanges K for guiding the lever against the stock L. This stock has the groove L' therein forming a seat for the lever and the frame is attached to the stock by screws L² engaging rearwardly extending 45 ears G' thereon which embrace a portion of the stock and a screw L³ engaging the top of the frame at its rear end.

50 Slidably engaging the barrel A is a plunger assembly of the following construction; M is

the plunger or piston fitting within said barrel and having the usual forward tubular member N which enters the true barrel C mechanically displacing the projectile and supplying the compressed air for accelerating the same. O is a bifurcated plunger shank 55 preferably formed from a single sheet metal blank fashioned to form a cylindrical forward portion O' and a bifurcated rearwardly extending portion O². The plunger M has the reduced shank M' which engages the cylindrical portion O' to which it is attached by a pin M². At the rear end of the bifurcated portion O² is a cross head O³ forming a bearing for engagement with the lever J as herein- 60 after set forth. S is a coil spring surrounding the plunger shank O and abutting at its forward end the plunger M. P is a spring abutment which fits between and is guided by the concave segments forming the bifurcations O². This abutment has at its front end 65 the reduced portion P' which extends into the rear convolutions of the spring S whereby the spring holds the abutment in place. In rear of this portion are the shoulders P² against which the spring abuts and in rear of these shoulders is the cam portion P³ which has a cammed end surface P⁴. Between this cammed end surface and the cross head O³ projects the curved end J' of the lever J.

70 The arrangement is such that when the lever is moved away from the stock the end J' thereof engaging the cross head O³ will carry the whole plunger assembly rearward until the cross head O³ engages the sear while the opposite movement of the lever J will 75 force the abutment P forward compressing the spring between the same and the plunger M. Furthermore, during the latter part of this forward movement, the leverage is increased in power so that the final compression 80 of the spring may be effected with less exertion on the part of the operator. Also the cammed end surface P⁴ and the end portion 85 J' of the lever are so shaped that the last portion of the movement is within the angle of friction thereby holding the lever in its 90 normal position and avoiding any tendency of the lever swinging from its normal position under the force exerted by the compressed spring.

95 It has been stated that the cross head O³ engages the sear. Said sear is formed upon a trigger Q by the hook Q' and a spring R

engaging lugs Q^2 on the trigger and a bearing on the stock yieldably forces the sear into position to engage the cross head.

With the construction as described, the various elements may be easily and quickly assembled first by assembling the plunger assembly consisting of the plunger M , bifurcated plunger shank O pinned to the reduced shank M' of the plunger, the coil spring S and the abutment P , the cross head being preferably the last element inserted and secured in place. With this assembly the spring yieldably holds the abutment member from accidental disengagement by reason of fitting over the reduced forward end portion thereof and also by reason of forcing this abutment member against the cross head. The plunger assembly is then placed within the false barrel A with the abutment member P extending vertically and depending through the slot A' extending longitudinally of the rear portion of the false barrel. The trigger Q is secured to the frame G as by means of the pivot pin Q^3 and the spring R is secured in a bore in the stock L after which the frame may be mounted upon and secured to the stock with the spring R properly engaging the lugs Q^2 upon the trigger. The lever J is then secured to the frame by means of the pin J^2 . This false barrel with the plunger assembly is next carried into the frame G . Upon carrying the false barrel and plunger assembly into the frame G the ends J' of the lever J will clear the lower edge of the cross head O^3 when the lever is in its normal position and this end comes into contact with the cammed end surface P^4 of the spring abutment P . To more readily continue the inward movement of the false barrel into the frame the lever is then swung to engage the cross head O^3 and release the compression of the coil spring S at the same time drawing the false barrel inward to permit the insertion of the pin A^2 through the lower front portion of the frame and the notch F of the reinforcement strip D secured to the false barrel.

In operation when the lever J is moved forward from its normal position adjacent the stock the end J' thereof engaging the cross head O^3 will carry the plunger rearward until the sear Q' on the trigger Q engages the cross head O^3 . The lever is then pulled back to a position against the stock and in doing so forces the abutment member P forward. This abutment is guided during such movement by the concave segments forming the furcations O^2 . At the completion of the movement of the lever its engagement with the cammed end surface P^4 is within the angle of friction thereby holding the parts in this position. The pulling of the trigger Q releases the sear Q' from the cross head O^3 and permits the discharge of the gun by reason of the plunger moving forward. This plunger is limited in its forward movement

by coming into contact with the plunger abutment B so that the cross head O^3 cannot come into contact with the spring abutment P to damage the gun.

The advantages of my improvement are, first, the simplicity and low cost of construction; second, ease in assembling; third, reduced power required for the compression of the plunger actuating spring. In addition to these, the most important advantage is that there is no possibility of pinching the hand or fingers between the lever and stock or lever and barrel since the reaction of the spring is in the opposite direction.

What I claim as my invention is:

1. In a gun, the combination with a barrel, of a plunger or piston therein, a bifurcated plunger shank extending rearward therefrom and having a cross head or bearing at its rear end, a spring sleeved on said shank, a spring abutment for engaging the rear end of said spring slideable between the furcations of the shank and having a reduced portion extending into the rear portion of said spring and a lever having its end between said cross head and spring abutment adapted to move the whole plunger assembly rearward to engage said cross head with the sear and to move the spring abutment forward to compress the spring.

2. In a gun, the combination with a barrel, of a plunger or piston therein, a bifurcated plunger shank having a cross head or bearing at its rear end, a spring sleeved on said shank, a spring abutment between the furcations of said shank and slidably engaging the same to be guided thereby, the said spring being arranged to maintain the said abutment in place, a frame to which said barrel is secured, a lever fulcrumed in said frame having its end inserted between said cross head and spring abutment, the latter being so fashioned as to be within the angle of friction when the lever is in its normal position.

3. In a gun, the combination with a stock, of a frame, a lever fulcrumed on said frame and normally lying adjacent to said stock, a barrel removably engaging said frame, a plunger in said barrel, a bifurcated plunger shank extending rearward therefrom, a spring sleeved on said shank, a spring abutment slidably engaging said shank and having a bearing portion with which the inner end of said lever is engaged, the said plunger, plunger shank, spring and spring abutment being removable as a unit from the said barrel, an opposed bearing on said shank for said lever through which said plunger, spring and abutment may be moved rearward, a sear for engaging said opposed bearing when in its rear position whereby it is held from movement during the forward movement of said spring abutment under the actuation of said lever, and a trigger for releasing said sear.

4. In a gun, the combination with a stock

of a frame attached thereto, a lever fulcrumed on said frame normally lying adjacent to said stock and having its inner end projecting within the frame, a barrel removably engaging said frame, a plunger within said barrel, a rearwardly extending plunger shank having a bearing for engaging said lever, a spring sleeved upon said shank, a spring abutment slidably engaging said shank and provided with an opposed bearing for said lever, the said spring abutment being maintained in engagement with the said shank by the said spring, a trigger pivotally engaging said frame, and a sear on said trigger with which the bearing on said shank is engaged when moved rearward by said lever.

5. In a gun, the combination with a stock and a barrel, of a frame formed from a sheet metal blank bent into a U-shaped section with inwardly extending abutting flanges in its forward portion for embracing said barrel and depending spaced flanges in its central portion, a lever fulcrumed to said depending spaced flanges and having its inner end projecting within the frame, a spring plunger mechanism operatively engaging said lever and means including a wedge-shaped member having a transverse groove carried by the barrel and a pin insertable through the said frame for detachably locking said barrel and frame to each other.

6. In a gun, the combination with a barrel, of a plunger engaging said barrel, a plunger shank formed from a sheet metal blank bent into cylindrical form and cut away to form diametrically opposed segments, a spring sleeved on said shank, a spring abutment between said segments having a bearing portion slidably engaging the concave surfaces thereof, the said spring and spring abutment being removable as a unit with the said plunger, a lever engaging said spring abutment and an opposed bearing on said shank,

and a sear for engaging said opposed bearing when said plunger assembly is moved rearward by said lever whereby the forward movement of said spring abutment by said lever will compress the spring. 45

7. In a gun, the combination with a barrel, 50 of a plunger or piston therein, a plunger shank extending rearward from said plunger and having a bearing at its rear end, a spring sleeved on said shank, a spring abutment for engaging the rear end of said spring guided 55 by said shank and having a portion surrounded by said spring and a lever having an end between said bearing and spring abutment adapted to move the whole plunger assembly 60 rearward to engage said bearing with the sear of the gun and to move said spring abutment forward to compress the spring.

8. In a gun, the combination with a barrel, 65 of a plunger or piston therein, a plunger shank extending rearward therefrom, a spring sleeved on said shank and engageable with said plunger or piston, a spring abutment for engaging the rear end of said spring having a portion extending into the spring and means for moving said plunger shank 70 rearward to engage the same with the sear of the gun and to move the spring abutment forward to compress the spring.

9. In an air gun, the combination with a barrel, 75 of a plunger therein, a slotted plunger shank extending rearwardly therefrom, a spring sleeved on said shank and engageable with said plunger, a spring abutment for engaging the rear end of said spring slidable in the slot of said shank and having a reduced 80 portion surrounded by the rear convolutions of said spring, and means for moving the whole plunger assembly rearward to engage the rear end of said shank with the sear and to move the spring abutment forward to compress the spring. 85

In testimony whereof I affix my signature.
CHARLES F. LEFEVER.
